US00D599023S

(12) **United States Design Patent**
Huffman

(10) **Patent No.:** **US D599,023 S**
(45) **Date of Patent:** **** Aug. 25, 2009**

(54) **OPPOSING DENTAL MODEL BASE
QUADRANT**

(76) Inventor: **Ronald E. Huffman**, P.O. Box 68440,
Oro Valley, AZ (US) 85737

(**) Term: **14 Years**

(21) Appl. No.: **29/323,426**

(22) Filed: **Aug. 26, 2008**

Primary Examiner—Charles A Rademaker

(74) *Attorney, Agent, or Firm*—Holland & Hart, LLP

(57) **CLAIM**

The ornamental design for opposing dental model base quadrant, as shown and described.

DESCRIPTION

FIG. 1 is a front top perspective view of an opposing dental model base quadrant showing my new design;

FIG. 2 is a rear top perspective view of thereof;

FIG. 3 is a front bottom perspective view thereof;

FIG. 4 is a rear bottom perspective view thereof;

FIG. 5 is a top view thereof;

FIG. 6 is a bottom view thereof;

FIG. 7 is a front view thereof;

FIG. 8 is a rear view thereof;

FIG. 9 is a left side view thereof; and,

FIG. 10 is a right side view thereof.

The portions of the article in broken lines are shown for illustrative purposes only and form no part of the claimed design.

1 Claim, 4 Drawing Sheets
